(57) **CLAIM**

The ornamental design for an indirect heat exchanger tube
controlled wrinkle bend, as shown and described.

DESCRIPTION

FIG. 1 is a front perspective view of an indirect heat
exchanger tube controlled wrinkle bend;

FIG. 2 is a right side view thereof, the left side view being
a mirror image thereof;

FIG. 3 is a front view thereof;

FIG. 4 is a rear view thereof; and,

FIG. 5 is a top view thereof, the bottom view being a mirror
image thereof.

The broken lines in the drawings illustrate portions of the
indirect heat exchanger tube controlled wrinkle bend that
form no part of the claimed design.

The dot-dash-dot broken lines in the drawings define bounds
of the claim and form no part thereof.

The indirect heat exchanger tube controlled wrinkle bend is
shown with a symbolic break in its length. The break lines
and the appearance of any portion of the indirect heat
exchanger tube controlled wrinkle bend between the break
lines form no part of the claimed design.
